UNITED STATES PATENT OFFICE.

ARTHUR McDougall DUCKHAM, OF ASHSTEAD, ENGLAND.

VERTICAL RETORT.

1,171,183.

Specification of Letters Patent.

Patented Feb. 8, 1916.

Application filed May 19, 1915. Serial No. 29,148.

To all whom it may concern:

Be it known that I, ARTHUR McDougall DUCKHAM, a subject of the King of Great Britain, residing in Ashstead, Surrey, England, have invented certain new and useful Improvements in Vertical Retorts, of which the following is a specification.

In operating vertical retorts for carbonizing coal or the like, it has been proposed to provide ports at different levels in the side of the retort so that the gases and volatile products produced in different zones may escape from the respective zones without having to traverse the hot charge in the rest of the retort. The separate collection of the products from the several zones is an obvious modification of this method of working.

The requirements of a gas-works or coking-works with regard to the quality and quantity of the by-products are by no means constant. Hitherto, however, there has been a lack of flexibility in the vertical retort in this respect. Slight variations, both qualitative and quantitative, have been possible by varying the dimensions and temperature of what has come to be called the free space at the top of the retort, but the variations are not adequate for all requirements.

The present invention relates to a construction of vertical retort for carbonizing coal or the like, whether for gas-making or for coke-making, in which the gases and volatile products may be withdrawn from the several zones of the retort and collected either separately or together and in a rapidly cooled condition or, by a modification of the construction, after subjection to more or less considerable heating.

The construction comprises a flue connected with ports at different levels in the wall of the retort and adapted to be subdivided into two or more collecting chambers each having its own off-take, or to be used as a single collecting chamber, and situated in such a position relatively to the heating flues of the setting that the products escaping into it are not subjected to any further heating but are cooled as rapidly as may be. This construction alone affords considerable flexibility as compared with the known suggestion of merely collecting the products from different zones separately; since it is possible to collect together the products from two or more zones while in the condition which they

have directly they leave the retort, with a result different from that which ensues when the separately collected products are subsequently mixed. Furthermore, no previous construction has taken account of the necessity for removing the collecting flue from the influence of the heating wall of the retort. In order, however, that the nature of the products may be varied by further cooling or by heating them, the invention also provides flues which can be traversed by cold air or can be heated at will as a whole or in portions to suitable temperatures, and are situated alongside the collecting flues, so that the products may be further cooled or heated in any one or all of the chambers into which the collecting flue can be subdivided. This construction having the heating flues is illustrated in the accompanying drawings, in which—

Figure 1 is a vertical section through the retort and Fig. 2 is a horizontal section on line 2—2 of Fig. 1.

a is the retort which has the long rectangular cross section now well known. In the wall forming the end of this rectangle are the gas ports *b* at different levels; they open into the collecting flue *c* in which are dampers *d* for subdividing it into as many compartments as there are ports (except that the top compartment serves two ports) and an off-take *e* for each such compartment adapted to be connected with an exhauster. On each side of the flue *b* is a heating flue *f*, in this case connected with the heating flues *g* of the retort and heated by the same gases under control of suitable dampers. Obviously, however, these flues may be heated separately from the flues *g*.

With dampers *d* in the positions shown the products from three zones of the retort are collected each separately, but if the dampers are withdrawn and the two lower off-takes closed, the products from all the zones will be collected together from the top off-take. The flues *f* may be similarly provided with dampers to sub-divide them into compartments corresponding with those of the collecting flue, and each such compartment may be separately connected with the supply of heat and the waste gas flue, so that each compartment of the collecting flue may be heated to a desired temperature.

Having thus described the nature of this invention and the best means I know of carrying the same into practical effect, I claim:

1. A vertical retort for carbonizing coal or the like comprising heating flues, a number of ports for the escape of products at different levels in the wall of the retort, a collecting flue situated in a position removed from the said heating flues, means for subdividing the said collecting flue into compartments, means providing passage for products from the said ports to the said compartments respectively and an off-take for products in each compartment. 45
2. A vertical retort for carbonizing coal or the like comprising heating flues, a number of ports for the escape of products at different levels in the wall of the retort, a collecting flue situated in a position removed from the said heating flues and such that the said ports open into it, dampers subdividing the said collecting flue into compartments such that each of the said ports opens into a separate compartment, an off-take for products in each compartment, and flues close to the said collecting flue adapted to receive a medium for varying the temperature of the collecting flue. 50
3. A vertical retort for carbonizing coal or the like comprising heating flues, a number of ports for the escape of products at different levels in the wall of the retort, a collecting flue into which the said ports open and flues close to but entirely independent of the said collecting flue and adapted to receive a medium for varying the temperature of the collecting flue. 55
4. A vertical retort for carbonizing coal or the like comprising heating flues, a number of ports for the escape of products at different levels in the wall of the retort, a collecting flue situated in a position removed from the said heating flues, means for subdividing the said collecting flue into compartments, means providing passage for products from the said ports to the said

compartments respectively, an off-take for products in each compartment, and flues close to the said collecting flue adapted to receive a medium for varying the temperature of the collecting flue. 60

5. A vertical retort for carbonizing coal or the like comprising heating flues, a number of ports for the escape of products at different levels in the wall of the retort, a collecting flue situated in a position removed from the said heating flues and such that the said ports open into it, dampers subdividing the said collecting flue into compartments such that each of the said ports opens into a separate compartment, an off-take for products in each compartment, and flues close to the said collecting flue adapted to receive a medium for varying the temperature of the collecting flue. 65
6. A vertical retort for carbonizing coal or the like comprising heating flues, a number of ports for the escape of products at different levels in the wall of the retort, a collecting flue, means for subdividing the said collecting flue into compartments, means providing passage for products from the said ports to the said compartments respectively and flues close to the said collecting flue and similarly subdivided into compartments each adapted to receive a medium for varying the temperature of the corresponding compartment of the collecting flue. 70

In testimony whereof I have signed my name to this specification in the presence of two subscribing witnesses.

ARTHUR McDougall DUCKHAM.
